LOCKING DEVICE

Filed March 13, 1931

Joseph S. Paulson INVENTOR

INVENTOR:
BY *Victor J. Evans & Co.*

HIS ATTORNEYS.

UNITED STATES PATENT OFFICE

JOSEPH S. PAULTON, OF CHICAGO, ILLINOIS

LOCKING DEVICE

Application filed March 13, 1931. Serial No. 522,367.

This invention relates to certain novel improvements in locking devices, and has for its principal object the provision of an improved construction of this character which 5 will be highly efficient in use and economical in manufacture.

It is an object of this invention to provide a locking device for refrigerator doors and to construct the same so that it will occupy a 10 minimum of space in width since it is necessary that the device be mounted, in many types of refrigerators now in use, on a parting strip disposed between the free edges of two doors on the refrigerator.

15 It is another object of the invention to provide a locking device which is so constructed that unauthorized opening of a refrigerator locked therewith will be effectively prevented, and the device is so constructed that once 20 assembled in place it cannot be taken apart by an unauthorized person.

Other objects will appear hereinafter.

The invention consists in the novel combination and arrangement of parts to be 25 hereinafter described and claimed.

The invention will be best understood by reference to the accompanying drawing showing the preferred form of construction, and in which:

30 Fig. 1 is a side elevational view of a typical refrigerator door showing the invention associated therewith;

Fig. 2 is a sectional view of the locking device on line 2—2 in Fig. 1;

35 Fig. 3 is a sectional view on line 3—3 in Fig. 2;

Fig. 4 is a sectional view on line 4—4 in Fig. 3;

Fig. 5 is a fragmentary view similar to Fig. 3, but showing the parts of the locking device in a different position; and

Fig. 6 is a perspective view of certain elements of the locking device.

In the drawing, wherein a practical embodiment of the invention is illustrated, a refrigerator is generally indicated at 10 and includes a door 11 hinged thereto as at 12. On the door 11 is mounted a latch structure, generally indicated at 13 and of any approved type since the same forms no part of this invention, and this latch structure 13 includes a

handle 14 which is pivotally mounted as at 21 (Fig. 3), and this latch structure 13 includes a tongue 15 which is associated with a groove 16 in a bracket 17 that is screwed to the refrigerator 10 as at 18. By pressing 55 downwardly on handle 14 the latch tongue 15 may be lifted out of groove 16, over the shoulder 19 of bracket 17 and when the door 11 is swung into closed position the tongue 15 will ride up the face 20 (Fig. 2) of bracket 17 and 60 reenter the groove 16. The present invention provides a device for locking the latch tongue 15 in the groove 16 of the bracket 17, and this device will now be described.

The bracket 17 includes a foot 22 which 65 is secured to the wall 10 by screws 23 and this foot 22 provides the back wall of the housing 24 of the improved latch structure generally indicated at 25. The side walls 26 of the housing 24 are detachably secured to 70 the back wall 22 by screws 27 (Fig. 4).

Slidably mounted in a boss 28 formed on the inner side of front wall 29 of housing 24 is a plunger 30 through which is extended a pin 31 and on plunger 30 between pin 31 75 and the top wall of boss 28 is a coil spring 32. On the lower end of plunger 30 is a block 33 which is adapted to slide in the housing 24 and through its open lower end 34 so as to lock the latch tongue 15 in the groove 16. 80 On the upper end of plunger 30 is a reduced portion or head 35 on the top of which is mounted, as by screws 36, an arcuate or concave plate 37, the plate 37 being an arc of a circle described by rotation of a cam 38, 85 which will be described more fully hereinafter. As has been stated hereinbefore, it is desirable that in a latching device for refrigerators, the walls 26 be as close together as possible since the locking device 90 must frequently be mounted on a narrow parting strip between two doors of the refrigerator 10, and in order to make the housing 24 as narrow as possible and yet permit the cam 38 to be rotated through an arc sufficient to depress the plunger 30 so that block 33 will lock tongue 15 in groove 16 the cam 38 is constructed and arranged in a manner now to be described.

95 Rotatably mounted in an annular shoulder 100

39 that is disposed in the front or outside of front wall 29 of housing 24, and in a fixed sleeve 40 that is disposed on the inside of wall 29, is a stub or key shaft 41 (Fig. 5) which has a segmentally formed end 42 that is fitted into a slot 43 in a plate 44 so that the plate 44 will rotate with shaft 41 when a suitable key 45 is inserted into a key slot formed in shaft 41.

10 Two similar slots 46 are formed in the cam plate 38 and this cam plate 38 is slidably mounted on plate 44 by means of screws 47 inserted through the slots 46 into plate 38. Formed in the plate 44 is a slot 48 and on the side of the cam plate 38 that is disposed toward the plate 44 a lug 49 is provided. A cam surface 50 is provided on the sleeve 40.

The operation of the device is as follows: 20 In unlocked position the plunger 30 will be disposed as in Figs. 2 and 3, and the block 33 will be upraised so as to permit the latch tongue 35 to be lifted out of groove 16 and in this position of the parts of the device lug 25 49 will be disposed in slot 48 (Fig. 3). However, when the shaft 21 is rotated counterclockwise, as seen looking in from the right hand side in Fig. 2, the lug 49 will travel down the cam surface 50 and this cam surface 30 has a rise in its lower end portion (see Figs. 3 and 6) so that the lug 49 will be forced out of the slot 48 as said lug travels 35 down the cam surface 50 (see Figs. 3 and 6) whereby said lug 49 will be unable to reenter the slot 48 since said lug 49 will then be bearing against the rise on the cam surface 50. When, therefore, the lug 49 engages the 40 arcuate plate 37 the plunger 31 and block 33 will be depressed against the action of spring 32 and thereby lock latch tongue 15 in the bracket groove 16. To open the locking device, the key 45 will be manipulated to rotate 45 shaft 41, plate 44, plate 38 and lug 49 in a counterclockwise direction as seen in Fig. 5, which will cause lug 49 to travel up off the 50 rise on the cam surface 50 and lug 49 will then reenter slot 48 in plate 44, thus releasing plate 37, plunger 31 and block 33 and spring 32 will then act on the plunger 31 to raise block 33 and thereby permit latch tongue 15 to be lifted out of groove 16.

It is apparent that while the hereinbefore described locking device is particularly adapted for use in connection with refrigerators it may be used in any manner in which a locking device of its type may be employed and it is not intended to limit the use of the invention to refrigerators.

60 While I have illustrated and described the preferred form of construction for carrying my invention into effect, this is capable of variation and modification without departing from the spirit of the invention. I, therefore, do not wish to be limited to the 65 precise details of construction set forth, but

desire to avail myself of such variations and modifications as come within the scope of the appended claims.

Having thus described my invention, what I claim as new and desire to protect by Letters Patent is:

1. In a locking device, a housing, a spring urged plunger slidably mounted in said housing, an arc-shaped plate on one end of said plunger, a key-slotted shaft rotatably mounted in the housing, a member providing a cam surface in said housing, a cam rotatable with said shaft, and a lug on said cam, a plate rotatably mounted on said shaft between said cam surface and said cam and having a slot 75 formed in the periphery thereof in which said lug is disposed when the device is in unlocked position whereby upon rotation of said shaft in one direction said lug will travel over said cam surface and be forced 80 out of said slot to engage and depress said plunger and upon rotation of said shaft in the opposite direction said lug will disengage 85 said arc-shaped plate and reenter said slot.

2. In means for actuating a slidably mounted spring urged latching plunger, an arc-shaped plate on one end of said plunger, a key-slotted rotatable shaft, a cam surface, a plate rotatable with said shaft and having a slot formed therein, a cam rotatable with said shaft and including a lug disposed in said slot when the plunger is in unlatched position, whereby upon rotation of 95 said shaft said lug will travel over and be forced by said cam surface out of said slot and engage said arc-shaped plate and force 100 said plunger into latching position.

3. In means for actuating a slidably mounted spring urged latching plunger, an arc-shaped plate on one end of said plunger, a key-slotted rotatable shaft, a cam surface, a plate rotatable with said shaft and having a slot formed therein, a cam rotatable with said shaft and including a lug disposed in said slot when the plunger is in unlatched position, whereby upon rotation of 110 said shaft said lug will travel over and be forced by said cam surface out of said slot and engage said arc-shaped plate and force 115 said plunger into latching position, and upon rotation of said shaft in the opposite direction said lug will reenter said slot and disengage said arc-shaped plate and said plunger thus be retained in unlatched position.

4. In means for actuating a slidably mounted spring urged latching plunger, an arc-shaped plate on one end of said plunger, a key-slotted rotatable shaft, a cam surface, a plate rotatable with said shaft and having a slot formed therein, a cam rotatable with said shaft and including a lug disposed in said slot when the plunger is in unlatched position, whereby upon rotation of 125 said shaft, said lug will travel over and be forced by said cam surface out of said slot and engage said arc-shaped plate and force said plunger into latching position.

said lug will travel over and be forced by said cam surface out of said slot and engage said arc-shaped plate and force said plunger into latching position, said cam having slots 5 formed therein, and connecting elements extended through said slots into said second named plate permitting a limited sliding movement of said cam and lug with respect to said last named plate and slot.

10 5. In means for actuating a slidably mounted spring urged latching plunger, an arc-shaped plate on one end of said plunger, a key-slotted rotatable shaft, a cam surface, a plate rotatable with said shaft and having 15 a slot formed therein a cam rotatable with said shaft and including a lug disposed in said slot when the plunger is in unlatched position, whereby upon rotation of said shaft said lug will travel over and be forced 20 by said cam surface out of said slot and engage said arc-shaped plate and force said plunger into latching position, and upon rotation of said shaft in the opposite direction said lug will reenter said slot and disengage 25 said arc-shaped plate and said plunger thus be retained in unlatched position, said cam having slots formed therein, and connecting elements extended through said slots into said second named plate permitting a limited 30 sliding movement of said cam and lug with respect to said last named plate and slot.

6. A device of the character described comprising a latching element including a head, a rotatable shaft, a cam surface fixed relative 25 to the shaft, a portion rotatable with said shaft and having a slot provided therein, a member rotatable with said shaft and including a projecting portion adapted to ride said cam surface and normally disposed in said 40 slot when said latching element is in ineffective position, whereby upon rotation of said shaft and said members said projecting portion will travel over said cam surface and be forced thereby out of said slot into engagement 45 with said head to move said latching element into effective position.

7. A device of the character described comprising a latching element including a head, a rotatable shaft, a cam surface fixed relative 50 to the shaft, a portion rotatable with said shaft and having a slot provided therein, a member slidably mounted on said portion, rotatable with said shaft and including a projecting portion adapted to ride said cam 55 surface and normally disposed in said slot when said latching element is in ineffective position, whereby upon rotation of said shaft and said members said projecting portion will travel over said cam surface and be forced thereby out of said slot into engagement 60 with said head to move said latching element into effective position.

In testimony whereof I affix my signature.
JOSEPH S. PAULTON.
